UNITED STATES PATENT OFFICE

JUSTUS J. ROSS, OF HUNTINGTON, WEST VIRGINIA

EXTENSION-RAIL CLIP

Application filed April 23, 1929. Serial No. 357,492.

This invention relates to the construction of clips for mine ties and rails, and has special reference to means for temporarily securing extension rails in inverted position in order that they may serve as a temporary track at the working face of the mine until such time as the face is moved back sufficiently to permit rails to be laid in upright position in the usual manner; thereby avoiding the use of short pieces of rail which often cause derailment with a consequent loss of time to the coal loader as well as an expense to the operator in replacing the car.

An object of the invention resides in the provision of a clip of inexpensive construction which may be readily and quickly applied to the ties so as to firmly and securely lock the inverted rails in place, and which may be removed with equal facility.

Another object of the invention consists in so constructing the clips that they may be operated by unskilled labor to provide the proper gauge and without danger of spreading in rails or the like, due to faulty application of the fastening means.

A further object of the invention resides in the provision of clips which may be applied without the use of special tools, thereby further facilitating the laying of the extension rails by the ordinary help found about the mines.

Other objects and advantages of the invention will be apparent from the following description when taken in connection with the accompanying drawings; in which

Figure 1 is a plan view, partly broken away, showing the usual arrangement of inverted extension rails to provide a track extension for the working places of a mine.

Figure 2 is a vertical section on line 2-2 of Figure 1, showing one of my novel clips for locking the rail in position.

Figure 3 is a fragmentary sectional view on the line 3-3 of Figure 1 showing a tie secured to the bases of the inverted extension rails so as to serve as an abutment to prevent cars from running off the end of the track.

Figure 4 is a detail perspective view showing the extension rail clip of Figure 2 as sepa-

rated from main rail clip with which it is intended to cooperate.

Figure 5 is a sectional view similar to Figure 2, but showing a different arrangement of wedge members.

Figure 6 is a side elevation of a modified form of clip shown in operative position.

Figure 7 is an end view of the clip shown in Figure 6.

Figure 8 is a sectional view through an extension rail showing another type of clip in side elevation.

Figure 9 is a sectional view taken on line 9-9 of Figure 8.

Figure 10 is a sectional view of a still further modified form of extension rail clip; and

Figure 11 is a detail view of the clip shown in Figure 10, parts being broken away to show the details of construction.

Referring to the drawings in greater detail and especially to Figures 1 to 5 inclusive, the numeral 1 indicates a mine tie of any desired construction, preferably of metal, and provided with alignment lugs 2 and rail securing clips 3. These ties, of course, are laid in the usual manner and the rails 4 are secured in position on the ties by means of the rotatably-mounted clips 3.

When laying rails at the working place in a mine it is quite often found desirable, due to the limited space, to invert the rails and clamp the ends thereof against the sides of the upright rails as indicated in Figures 1 and 2. By this means a track may be temporarily increased in length from time to time until it is found desirable to lay the increased length of track in the usual form with the rails in upright position. The present invention relates to means for quickly and accurately securing these inverted rails in position.

As clearly indicated in Figures 2, 4 and 5, the outside clip 3 is provided with an aperture 5 adapted to receive the L-shaped finger 6 of the extension clip 7. In applying the extension clip to the rail clip, the latter is first turned so that its aperture 5 overhangs the side of the tie; the finger 6 may then be inserted into the aperture and the clip 3 turned to the position shown in Figures 2

and 5. In this position the flat portion of the finger is in contact with the upper surface of the tie and the extension clip is thus locked against disengagement from the tie 5 clip until the latter is again turned to a position in which its aperture 5 overhangs the side of the tie.

The extension clip 7 is provided with a channel or pocket 8 on its upper end for the 10 reception of a wedge 9 which is driven into the space between the back wall of the pocket and the web of the inverted rail so as to tightly clamp the inverted rail against the overlapping portion of the upright rail or 15 against the clip on the opposite side of the rail. In Figure 5 I have shown an additional wedge 10 for use in places where the tie is not solidly supported on the ground or floor; this second wedge thus serves to prevent sagging 20 of the tie away from the rail under such circumstances.

With the foregoing construction of extension clip and attaching means therefor it will be readily apparent that the inverted extension rails may be easily and quickly applied and removed without the use of skilled labor and without the use of any special tools, thereby avoiding delays which would otherwise be caused while waiting for the track to 30 be extended up to the working face of the mine.

In Figures 1 and 3 I have illustrated the use of a tie placed on the top of the inverted rails to serve as a bumper to prevent cars from 35 running off the end of the track; this is an ordinary and well known construction and forms no part of the present invention.

In Figure 6 I have shown a modified construction of extension clip in which the clip 40 20 is provided with one or more fingers 21 which are adapted to pass through openings 22 in the clip 3 and tie 1. In this embodiment of the invention it will be observed that the extension clip may be placed in rail securing 45 position while the clip 3 continues to serve as a fastening means for the upright rail 4. In this form as well as that previously described a wedge 23 is driven between the clip and the inverted rail so as to securely hold the 50 latter in place.

Figures 8 and 9 illustrate a still further embodiment of the invention in which the extension clip 30 is provided with a pair of fingers 31 bent back upon themselves so as to 55 engage over the edge of the clip 3 when the latter is turned through 180° from its rail engaging position. From an inspection of Figure 9 it will be apparent that one of the fingers or hooks 31 extends over the edge of the 60 clip 3 at one side of the tie while the other finger passes through an opening 33 in the plate so as to extend below the edge of the clip. The extension clip is thus anchored to the clip 3 and provides a bearing for the 65 wedge 34 which forces the inverted rail

against the upright rail so as to securely fasten the former and provide the proper gauge.

Another modified form of the invention is disclosed in Figures 10 and 11, in which the rivet which pivotally connects the clip 3 to the tie is provided with a supplemental head or button 42 for engagement with the key-hole slot 41 formed in the extension clip 40. As in the several previously described forms of 75 clips, the clip 40 is constructed to provide a pocket to receive one edge of the clamping wedge 43.

From the foregoing description it will be apparent that I have devised an extension clip which may assume a variety of forms but in all of which is provided means by which the clip may be readily and quickly applied to and removed from fastening position without the use of tools or skilled labor, and in which a pocket is provided for reception of the usual locking wedge. It will be further apparent that the extension rail clip as depicted herein is formed of a single piece of metal, is strong and durable in operation, and may be applied to the tie without mutilation of the latter.

In accordance with the patent statutes I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

What I claim as new and desire to secure by Letters Patent is:

1. In combination with a cross-tie, a rotatable clip associated with the tie for securing a rail in place on the tie, and a second clip detachably engaging the first-mentioned clip for the purpose described.

2. In combination with a mine tie, an inverted rail, a clip detachably associated with the tie, and a wedge for cooperation with the clip and rail to secure the latter in place.

3. In combination with a mine tie, an inverted rail, a clip detachably associated with the tie, a pocket formed in said clip and a wedge inserted in said pocket and forced into contact with the inverted rail to lock the latter in place.

4. In combination with a mine tie, a rail thereon, a clip for locking said rail in place, an inverted rail having a portion overlapping said first-mentioned rail, and a second clip detachably associated with said first-mentioned clip for securing said inverted rail in place.

5. In a track structure including a tie, a rail and a clip for securing said rail in place, a second clip associated with said first-mentioned clip and adapted to receive a

wedge member for locking an inverted rail in place.

6. In a track structure including a tie, a rail and a clip for securing said rail in place, said clip provided with a recess, and an extension rail clip provided with a projection adapted to be received in said recess.

7. In a track structure including a tie, a rail and a rotatably-mounted clip for securing said rail in place, said clip provided with a recess, and an extension clip provided with a projection adapted to be received in said recess.

8. In a track structure including a tie, a rail and a rotatably-mounted clip for securing said rail in place, said clip provided with an aperture in that portion thereof which extends over the base of the rail, an extension clip, and a projection on said extension clip adapted to be inserted into said aperture when the first-named clip is moved to non-securing position.

9. In a track structure including a tie, a rail and a rotatably-mounted clip for securing said rail in place, said clip provided with an aperture, an extension clip, and a projection on said extension clip, the parts being so proportioned that the projection may be inserted in the aperture in one position of the first-mentioned clip and locked against withdrawal from the aperture in another position thereof.

10. In a track structure including a tie, a rail and a rotatably-mounted clip for securing said rail in place, said clip provided with an aperture in that portion thereof which extends over the base of the rail, an extension clip, and an L-shaped projection on said extension clip adapted to be inserted into said aperture when the first-named clip is moved to a position so that the aperture extends over the edge of the tie and locked in said aperture when the first-named clip is swung to a position 180° from its rail securing position.

45 11. In combination with a mine tie, a rail thereon, a clip for locking said rail, a second clip, and a finger on said second clip for anchoring the same to said first-mentioned clip.

JUSTUS J. ROSS.
